D5-27

EX

D5379

OR D 16,592

DESIGN.

S. LOEWENHERZ.

ORNAMENTATION OF LEATHER, &c.

No D 16,592.

Patented Mar. 30, 1886.

UNITED STATES PATENT OFFICE.

SIGMUND LOEWENHERZ, OF NEW YORK, N. Y.

DESIGN FOR THE ORNAMENTATION OF LEATHER, &c.

SPECIFICATION forming part of Design No. 16,592, dated March 30, 1886.

Application filed February 13, 1886. Serial No. 191,903. Term of patent 3½ years.

To all whom it may concern:

Be it known that I, SIGMUND LOEWENHERZ, a citizen of the United States, residing at New York, in the county and State of New York, have invented and produced a new and original Design for Ornamenting Leather and other Fabrics, of which the following is a specification, reference being had to the accompanying drawing, forming part thereof.

10 My invention consists in a new design for ornamenting leather and other fabrics, such as are used in the manufacture of pocket-books, satchels, and other similar articles, my said invention being fully pointed out in the following specification and claim and illustrated in the accompanying drawing.

15 In the upper left-hand corner of the drawing is represented a castle, A, which is situated upon a rocky elevation at the foot of mountains overowering the same. The castle embodies in its architectural structure two spires, a, surmounted by slender pinnacles, and turrets a', and it is surrounded by a high defensive wall, b. A pathway leads from the 20 castle to a winding stream of water, B, which flows past the castle and is studded with vessels of various description. A rough bridge, B', spans the stream, and is arranged in line with the pathway to the castle. In the back-

25 ground is pictured a second castle with tall spires, said castle being situated upon the summit of the rocky mountains previously mentioned. In the foreground are grouped trees, together with other foliage, to represent

30 a forest, and here is pictured a huntsman, C, in pursuit of game, the rider being represented in the act of checking his steed. The hunting hounds are in a full run, as if giving chase to some game, and one hound is in advance while the other is in the rear of the 35 huntsman. Below this mountain view is shown a farm scene, and in the foreground thereof is pictured a horseman, D, apparently engaged in conversation with a person who is resting upon the bars of a rail fence on the opposite side. The horseman is holding his steed by the bridle with one hand and rests his other hand upon the fence. A dog occupies a position in close proximity to the horse.

40 To the right of the group is a fruit-tree with wide-spreading branches overshadowing the same. In the background is represented a occupying the space between the group and farm-house.

45 farm-house with its gabled shingle roof, a field

55 In the upper right-hand corner of the drawing is represented a landscape embodying a Swiss cottage, E, having a balcony, which extends round it, and a gable roof. A roadway passes the cottage, and to one side of the latter is an inclosure studded with trees and other foliage. In the foreground is represented a park with a sloping lawn, which is partially inclosed by a rail fence, and on the lawn are grazing deer and other animals. Fir-trees and fruit-bearing trees are shown standing in various parts of the park. Directly below this cottage scene is represented a castle, F, which is situated upon the summit of a craggy elevation, and is architecturally designed with a prismatic tower, F', having slender pinnacles with rounded crowns, extending from each corner thereof. The castle is also designed with other smaller towers and turrets, and in the lower part of the main structure is shown an arched doorway, f, to which leads a roadway from the valley below. On one side of the roadway is a substantially-constructed wall, f', which separates the same from an abrupt declivity. At the foot of this declivity in the valley is shown the perspective of a chapel, G, having a tall rounded steeple, g, and a gable roof. A fox, g', is passing along the roadway on a swift run. Interspersed with the just-described representations are branches bearing ivy-leaves H, oak-twigs I and acorns thereon, and other creeping plants, J, which offset and separate these various parts of the picture.

75 80 85 90 95 100
What I claim as new, and desire to secure by Letters Patent, is—

The design herein described and shown for the ornamentation of leather and other fabrics, consisting of the representation in relief of a castle, A, embodying in its architectural design spires a and turrets a', a bridged stream of water, B, and landscape in the background, substantially as described.

In testimony whereof I have hereunto set my hand and seal in the presence of two subscribing witnesses.

SIGMUND LOEWENHERZ. [L. S.]

Witnesses:

S. VAN ZANDT,
A. FABER DU FAUR, Jr.